UNITED STATES PATENT OFFICE.

JESSE B. YOUNG, OF RUSH, KENTUCKY.

MATCH-BOX.

1,396,545.

Specification of Letters Patent. Patented Nov. 8, 1921.

Application filed November 29, 1920. Serial No. 427,112.

To all whom it may concern:

Be it known that I, JESSE B. YOUNG, a citizen of the United States of America, residing at Rush, in the county of Boyd and

5 State of Kentucky, have invented new and useful Improvements in Match-Boxes, of which the following is a specification.

The object of the invention is to provide a single delivery match box adapted to ignite the matches as they are successively withdrawn therefrom and designed to be used as a pocket or portable holder or carrier for matches to protect the same against damage from moisture; and with this object in view the invention consists in a construction and combination of parts of which a preferred embodiment is shown in the drawing, wherein:

Figure 1 is a perspective view of the match box.

Fig. 2 is a longitudinal sectional view of the same.

Fig. 3 is a transverse section on the plane indicated by the line 3—3 of Fig. 2.

25 Fig. 4 is a plan view of the blank from which the body portion of the box is formed.

Fig. 5 is a similar view of one of the end walls.

Fig. 6 is a similar view of the blank from which the delivery tube is formed.

Figs. 7 and 8 are plan views respectively of the blanks from which the bracing piece and delivery tube bracket are formed.

The box consists of a blank such as indicated in Fig. 4 which is folded upon itself near its center to form a bottom 10 and side walls 11 which are contracted near their upper free edges to form a delivery seat 12 in which is revolvably mounted a delivery tube

40 13 consisting of the roll portion of the blank illustrated in Fig. 6. This tube is longitudinally slotted as shown at 14, the slot being formed by displacing the edges of the blank at an interval sufficient to permit of the pas-

45 sage of a match, so that when the slot is positioned by the rotation of the tube to communicate with the interior of the box a match from the storage compartment formed by the body of the box may drop laterally

50 thereinto whereupon the turning of the tube will cut off communication between the storage compartment and the tube and the tilting of the box toward one end will cause an end-wise movement of the match to expose

55 one end thereof in position to be grasped by the operator. The delivery end of the tube

as shown at 15 is contracted or reduced and internally corrugated or roughened as shown at 16 so that as the matches are withdrawn from the tube the frictional contact 60 of the head thereof with the roughened surface of the tube will ignite the same. Preferably the discharge end of the tube is slotted or notched to allow it to yield under the strain of drawing the match head there- 65 through, so as to prevent the wedging of the match head and an unnecessary amount of resistance to the withdrawal of the match.

The opposite end of the tube is open and is adapted to have matches fed thereinto to 70 charge the reservoir or storage compartment.

The blank shown in Fig. 6 from which the delivery tube is formed is provided with a lateral tongue 17 which is rolled or coiled 75 to form a knob arranged exteriorly of the box by which the tube may be turned to separate a match from the stock contained in the storage compartment.

The ends of the box are closed by end 80 walls 18 provided with lateral ears 19 which extend through slots 20 formed in the side walls, and the end edges of the latter are flanged as shown at 21 to fold over the end walls and thus provide a moisture excluding 85 receptacle. The end walls are also provided with lateral ears 22 which are bent inwardly into engagement with the contracted portion of the side walls to maintain the free edges of the blank forming said walls in proper 90 relation to properly house the dispensing or delivery tube.

The portions of the end walls which cover the ends of the delivery seat are provided with openings forming bearings for the de- 95 livery tube, and a bracket is arranged as shown at 23 to extend around the knob 17 to provide against end-wise displacement of the delivery tube while permitting the rotation thereon. In the construction illustrated 100 said bracket consists of an angular member 24 having a terminal tongue 25 engaged with the upper end of the adjacent end wall and having a bearing 26 for the trunnion 27 provided by the portion of the delivery 105 tube projecting beyond the plane of the knob 17, and a bracing piece 28 having reduced terminals 29 which are respectively engaged with openings in the adjacent end wall and the extremity of the angular mem- 110 ber 24.

It will be understood that in operation

- the delivery tube should be turned to register the receding slot thereof with the storage compartment whereupon the inversion of the box will cause a match to drop through 40
5 the slot into the tube, and by then turning the tube the remaining matches will be excluded while an end-wise tilting movement 45 of the box will cause the unheaded end of the match to project through the contracted 50
10 terminal of the tube where it may be grasped to permit of withdrawal and simultaneous ignition.

Having described the invention what is claimed as new and useful is:—

- 15 1. A match box having a storage compartment provided with a communicating tubular seat, and a dispensing or delivery tube revolvably mounted in said seat and provided with a longitudinal slot for communication 55
20 with the storage compartment, one end of said tube being contracted to resist the passage of a match head therethrough and being notched or slotted to exert a yielding 60 pressure upon the match head.
25 2. A match box having a storage compartment provided with a communicating tubular seat, and a dispensing or delivery tube revolvably mounted in said seat and provided with a longitudinal slot for communication 65
30 with the storage compartment, one end of said tube being contracted to resist the passage of a match head therethrough, said tube consisting of a blank of sheet metal to roll upon itself with its edges separated to 70
35 form said slot and having a lateral tongue coiled to provide an operating knob.
4. A match box having a storage compart-

ment provided with a communicating tubular seat, and a dispensing or delivery tube revolvably mounted in said seat and provided with a longitudinal slot for communication 40
45 with the storage compartment, one end of said tube being contracted to resist the passage of a match head therethrough, the bottom and side walls of the box being 45
50 formed of a blank of sheet metal doubled upon itself with the side wall portions contracted to form said seat, and end walls secured to the edges of the side walls and provided with bearings for said tube.

4. A match box having a storage compartment provided with a communicating tubular seat, and a dispensing or delivery tube revolvably mounted in said seat and provided with a longitudinal slot for communication 55
55 with the storage compartment, one end of said tube being contracted to resist the passage of a match head therethrough and being notched or slotted to exert a yielding 60 pressure upon the match head, the body portion of the box consisting of a blank of sheet metal doubled upon itself to form the bottom and side walls of which the free end edges are contracted to form said seat, end wall blanks being secured between the edges 65
60 of said side walls and having bearings for the delivery tube, and a bracket being attached to one of said end wall blanks to receive the knob at one end of the delivery tube.

In testimony whereof he affixes his signature.

JESSE B. YOUNG.
